UNITED STATES PATENT OFFICE.

JOHN GORDON PLEMMONS, OF DETROIT, MICHIGAN.

ENGINE.

Application filed November 1, 1920. Serial No. 421,146.

To all whom it may concern:

Be it known that I, JOHN G. PLEMMONS, a born citizen of the United States, residing at Detroit, in the county of Wayne and State of Michigan, have invented new and useful Improvements in Engines, of which the following is a specification.

This invention relates to a rotary engine more particularly designed for use with combustible fuel and the principal object of the invention is to revolve the rotor by a series of explosions which are arranged to take place at two opposite points simultaneously while a new charge is being drawn in at two other opposite points, said new charges being compressed and the exhaust gases expelled as the rotor is moving forwardly.

Another object of the invention is to form a pair of chambers between the rotor and an inner stationary part of the engine to act as suction and compression chambers and another pair of chambers between the rotor and an outer stationary part of the engine for acting as explosion chambers for the explosive gases.

Still another object of the invention is to provide spring controlled swinging abutments for the chambers for controlling the flow of gas thereto, said members being arranged in pairs with the springs of each pair working together to keep the swinging abutments in engagement with the walls of the rotor.

A further object of the invention is to provide lubricating means for the movable parts which act by centrifugal force.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a front view of an engine constructed in accordance with my invention.

Figure 2 is a rear view.

Figure 3 is a sectional view.

Figure 4 is a sectional view taken on line 4—4 of Figure 3. 55

Figure 5 is a sectional view taken on line 5—5 of Figure 2.

Figure 6 is an end view.

As shown in these views the body of the engine is formed of the inner stationary part 1 and the outer stationary part 2 which are so formed as to leave an annular space 3 between them which has one end opening out through one side of the body. A rotor 4 is located in this space, said rotor being formed with two ring shaped side pieces 5 and a cross piece 6, said cross piece having two portions concentric with and engaging the circular walls of the outer part and two portions concentric with and engaging the circular walls of the inner part, these concentric portions being connected together by the tangentially arranged intermediate portions. Thus the concentric portions which engage the outer part of the body form 75 abutments against which the expanding gases will act and these concentric portions also form a pair of inner chambers 7 while the other concentric portions form a pair of outer chambers 8, these chambers being completed by the circular walls of the inner and outer parts of the body. It will thus be seen that the rotor is of channel shape with the channel being formed upon its interior wall at two opposite portions and the other 85 two opposite portions having the channel formed upon the exterior thereof. The rotor has its outer end connected with the hub 9 by the circular plate 10, the outer periphery of which is curved and extends within the space between the inner and outer parts of the body. Said hub 9 is connected with the axle 11 which is journaled in the central part of the inner part of the body. Roller bearings 12 are arranged between the said 95 inner part and the axle.

The inner part 1 of the body is provided with four substantially semi-cylindrical chambers 13 which are arranged a quarter turn from each other and the outer part 2 of the body is provided with four similar chambers 14. A pair of swinging abutments 15 and 15' are arranged in each pair of the chambers 13 and 14, these members

being connected with the shafts 16 rotatably mounted in the body and carrying at their outer ends the coiled springs 17 which have their free ends connected together by the 5 link 18. These springs are so arranged that the members 15 and 15' are held against the inner and outer faces of the rotor.

As will be seen the chambers 13 will communicate with the chambers 7 of the rotor as 10 said rotor revolves while the outer chambers 14 will communicate with the chambers 8 of the rotor and said swinging abutment 15 will act to cut off one portion of each chamber 7 with the other portion during the 15 rotation of the rotor while the swinging abutment 15' will act to cut off one portion of each chamber 8 with the other portion as the rotor rotates. A small port 19 is formed in the wall of each of the chambers 13 and a 20 like port 20 is formed in the wall of each of the chambers 14, these ports being separated from the chambers 13 and 14 by the swinging abutment 15 and 15' and said swinging abutment 15 and 15' are each provided with 25 concaved faces 21 for connecting the ports 19 and 20 with the chambers 7 and 8 when the cut off members are extending into the chambers 7 and 8. A spark plug 22 extends into each of the recesses 20. A passage 23 connects each of the ports 19 with a port 20.

A carbureter 24 is secured to the front of the engine and a manifold 25 leads the explosive mixture from this carbureter into the chambers 13 and exhaust manifolds 26 are connected with outlet ports 27 communicating with the chambers 14.

It will be seen that a vacuum will be created in the front part of the chamber 7 in rear of the swinging abutments 15 so that 40 the explosive mixture is drawn from the carbureter through the manifold, into the chamber 13 and into that part of the chamber 7 in rear of the cut-off. Thus said chamber 7 is filled with the explosive mixture and the same action is taking place in 45 the opposite chamber 7. At this time the gas which was in the chambers in front of the swinging abutment at the beginning of the quarter turn is being forced into the ports 19, passages 23 and ports 20 where it is compressed so that at the end of this quarter revolution we have two opposite passages 23 and their ports filled with compressed 50 gases and the chambers 7 filled with gas ready to be passed into the next two passages.

During the same one quarter revolution the ignition took place in the two opposite 60 passages 23 which were filled with compressed gases so that these exploded gases acting against the abutments or humps of the rotor will drive the same forwardly, the expanding gases being confined between the humps and the swinging abutments 15.

65 During this same quarter revolution the

exhaust of previous work stroke is also driven out through the exhaust ports into the exhaust manifolds.

It will thus be seen that we have the four operations of intake, compression, explosion, 70 and exhaust all carried out every quarter revolution and on opposite sides of the rotor, thus making the ignition in pairs and giving four pairs of ignition per revolution. 75

Two operations are going on all the time, one in front and one behind each cut-off port. At all times opposite cut-off ports are performing the same function and are at the same period in that function. In other 80 words, the four operations of intake, compression, explosion, and exhaust go abreast or hand in hand by which means there is no idle stroke involved in the cycle. Hence, one pair of work strokes begin where the other 85 pair was completed; and the process is repeated continuously.

The springs 17 for the swinging abutments are so arranged that they will put forth their greatest pull at the time the 90 swinging abutments ride over the humps of the rotor and most need the pull.

The body of the motor is provided with the usual water jacket to which water is 95 provided in any desired manner.

The rotor is also provided with four rings 28, the outer pair of which contacts against the rotor while the inner pair expand against the rotor to prevent leakage of gases 100 from the sides.

I also place a flange 29 in each of the inner chambers 13, just back of each intake cut-off so as to secure a slight increase in the length of the intake stroke. This included with the long arc with a quarter turn of the rotor secures a great length of stroke. By having the ignition take place on opposite sides of the rotor at the same time the thrust is eliminated and the roller bearings 105 reduce friction to a minimum. 110

The engine is oiled by centrifugal force by providing an oil hoop 30 on the rear of the engine and which is adapted to rotate with the hub and this hoop is connected with the oil passages in the rotor by the radial tubes 31. This hoop 30 is open at one side as indicated at 32 and extending through this open side is a lubricant supply pipe 33 which has communication with a lubricant reservoir (not shown). 115 120

By my invention power can be taken from the hub or shaft, thus eliminating the transformation of power from a reciprocating to a rotary form by means of the crank shaft and its associated part. 125

It is thought from the foregoing description that the advantages and novel features of my invention will be readily apparent.

I desire it to be understood that I may 130 make changes in the construction and in the

combination and arrangement of the several parts, provided that such changes fall within the scope of the appended claims.

What I claim is:—

5. An engine of the class described comprising a body having an annular space therein, a rotor located in said space and formed with pairs of portions concentric with the casing, one pair of said portions being connected with the other pair, elements arranged tangential with respect to the casing, one pair of the portions forming interior chambers and the other pair exterior chambers, swinging abutments arranged in pairs and extending into said chambers and engaging the rotor, means for feeding an explosive charge to the rear side of one pair of swinging abutments, means for transferring compressed gas from the interior chambers to the exterior chambers, and means for firing the charge in front of the opposite swinging abutments, and means for exhausting the exploded gases.
10. An engine of the class described comprising a body having an annular chamber therein and inlet and outlet chambers arranged in pairs with the chambers of each pair arranged on each side of the annular chamber, a rotor in said annular chamber having outer concentric parts and inner concentric parts connected together by tangential parts, said parts forming interior suction chambers and exterior expansion chambers, inlet and outlet chambers, swinging abutments in the inlet and outlet chambers, spring means for holding said swinging abutments in engagement with the rotor, transfer passages extending from the inlet chambers to the outlet chambers, means for firing the charge in said passages and means for feeding the explosive mixture to the inlet chambers.
15. An engine of the class described comprising a body having an annular chamber therein, a rotor in said chamber having outer concentric parts and inner concentric parts joined together by tangential parts, said parts forming interior suction chambers and exterior expansion chambers, inlet and outlet chambers formed in the body and arranged in pairs with the chambers of each pair on each side of the annular chamber, swinging abutments in said chambers, spring means for holding said swinging abutments in engagement with the rotor, transfer passages connecting the inlet chambers with the outlet chambers, means for firing the charge in said passages, means for feeding the explosive mixture to the inlet chambers and a centrifugal lubricating device carried by the rotor.
20. An engine of the class described comprising a body having an annular chamber therein, inlet and outlet chambers arranged in pairs with the chambers of each pair located on each side of the annular chamber, a rotor in said annular chamber having outer concentric parts and inner concentric parts connected together by tangential parts, said parts forming interior suction chambers and exterior expansion chambers which communicate with the inlet chambers, swinging abutments in said inlet and outlet chambers, spring means for holding said swinging abutments in engagement with the rotor, a transfer passage connecting each inlet chamber with the outlet chamber, means for firing the charge in said passages, means for feeding explosive mixture to the inlet chambers, an axle passing through the body and rotatably mounted therein and means connecting one end of the axle with the rotor.
25. An engine of the class described comprising a body having an annular chamber therein and inlet and outlet chambers arranged in pairs with the chambers of each pair located on each side of the annular chamber, a rotor in said annular chamber formed of two outer concentric portions oppositely disposed and engaging the outer walls of the annular chamber and two other concentric portions engaging the inner walls of the chamber, said concentric portions being connected together by tangential portions, the outer concentric portions forming interior suction chambers and the inner concentric portions forming chambers for receiving the exploded gases, swinging abutments arranged in said inlet and outlet passages, spring means for holding said swinging abutments in engagement with the rotor, transfer passages connecting the inlet chambers with the outlet chambers, means for firing the charge in said passages and means for feeding the explosive mixture to the inlet chambers.
30. An engine of the class described comprising a body having an annular chamber therein and inlet and outlet chambers arranged in pairs and the chambers of each pair being located on different sides of the annular chamber, a rotor in said annular chamber, swinging abutments in said inlet and outlet chambers, shafts rotatably mounted in the body and carrying said swinging abutments, a coiled spring on each shaft, a link connecting the ends of the springs of each pair together, transfer passages connecting the inlet chambers with the outlet chambers, means for firing the charge in said passages and means for feeding the explosive mixture to the inlet chambers.

In testimony whereof I affix my signature.

JOHN GORDON PLEMMONS.
